COMBINED TABLE AND EASEL

James C. Cole, Redwood City, Calif.

Application May 25, 1955, Serial No. 36,197

Term of patent 14 years

(Cl. D33—14)

Fig. 1 is a perspective view of a combined table and easel showing my new design;

Fig. 2 is a side perspective view thereof, on a smaller scale, illustrating the top tilted for use as an easel; and

Fig. 3 is a perspective view similar to Fig. 2 but taken from the opposite side.

The dominant features of the design reside in the portions shown in full lines.

I claim:

The ornamental design for a combined table and easel, as shown and described.
